UNITED STATES PATENT OFFICE.

DANIEL W. COREY, OF ST. LOUIS, MISSOURI.

BOOT OR SHOE.

SPECIFICATION forming part of Letters Patent No. 741,012, dated October 13, 1903.

Application filed March 24, 1903. Serial No. 149,323. (No model.)

To all whom it may concern:

Be it known that I, DANIEL W. COREY, a citizen of the United States, residing in the city of St. Louis, State of Missouri, have invented 5 certain new and useful Improvements in Boots or Shoes, of which the following is a specification.

This invention appertains to improvements in boots and shoes, and relates more particularly to internal cushions therefor, the cushions being of such construction as to provide, first, an internal heel-cushion; second, a shank, and, finally, a spring-cushion located beneath the ball of the foot when the shoe is 15 worn, as will be hereinafter set forth.

In the accompanying drawings, which illustrate one embodiment of my invention, Figure 1 is a side view, partly in section, showing the invention applied to a shoe. Fig. 2 is a 20 bottom view of a shoe, the outer sole, shank, and heel being removed. Fig. 3 is a perspective view of a preferred form of spring, and Fig. 4 is a detail perspective view of an elastic block or heel-cushion.

25 In the make-up of a boot or shoe in accordance with my invention the inner sole A is attached to the upper in the usual manner, and such sole, immediately above the heel portion of the shoe, is cut through to provide a 30 flap a, the line of severance through the inner sole, which provides the flap, diverging from a point about on a line with the front portion of the heel rearward to where the side cuts join a rounded cut at the rear, as 35 will appear more fully by reference to Fig. 2. To the inner sole there is attached an inner lining a'.

To the outer side of the inner sole A there is attached a spring-bar, made up of a flat 40 strip of steel or other suitable material, having near one end a perforation b and perforations b' b'', positioned to be above the shank of the shoe. The end B' of the spring is attached to the flap, said end being bent at an 45 upward inclination and forward. Beyond this upward-inclined end there is an arch B², which overlies the shank of the shoe. Beyond such arch there is a part B³, which extends forward and terminates near the toe of 50 the shoe, such part B³ having an upward curve, the end being free to move forward

toward the toe, and the tendency of this arched part is to raise the insole under the ball of the foot to provide a cushion at that part of the shoe. The spring B is made fast 55 by tacks or other securing means to the rear end of the flap and to the portion of the insole above the shank.

The outer sole C at a point beneath the flap a is cut through or recessed to provide a cavity with beveled side walls for the reception of a rubber or elastic pad D, against which the spring-lifted flap will bear when depressed.

The construction shown provides a yielding 65 support for the heel and ball of the foot. It reinforces and keeps in shape the shank of the shoe, and when the improvement is applied to shoes the user is enabled to walk with greater ease and there is less jar than 70 when shoes of ordinary construction are worn.

Having thus described my improvement, what I claim as new, and desire to secure by Letters Patent, is—

1. A boot or shoe having an inner sole, a 75 longitudinal spring attached to said sole, the spring conforming to the shank and shaped to arch upward forward of the shank, the portion of the spring above the heel being inclined upward, to provide spring portions 80 to the front and in rear of the shank.

2. In a boot or shoe, an insole cut out to provide at the heel portion a flap, a spring attached to the flap to maintain the same inclined upward and rearward, and a cushion 85 with which the flap and spring engages when depressed, for the purpose set forth.

3. In a boot or shoe, an outer sole or shank having above the heel a recess the side walls thereof being beveled, an elastic pad maintained in the recess, an inner sole cut away above the pad to provide a flap and a spring with a rearward and upward projecting end attached to the flap and to the shank of the shoe. 90

In testimony whereof I have hereunto set my hand in the presence of two subscribing witnesses.

DANIEL W. COREY.
